UNITED STATES PATENT OFFICE.

GEORGE S. INGLE, OF INDIANAPOLIS, INDIANA; HOWARD WELLS,
ADMINISTRATOR OF SAID INGLE, DECEASED.

DRIVING-BELT.

SPECIFICATION forming part of Letters Patent No. 738,684, dated September 8, 1903.

Application filed July 17, 1902, Serial No. 115,997. (No model.)

To all whom it may concern:

Be it known that I, GEORGE S. INGLE, a citizen of the United States, residing at Indianapolis, in the county of Marion and State of Indiana, have invented a new and useful Driving-Belt, of which the following is a specification.

This invention relates to driving-belts of that class employed in transmitting power from one place to another, driving machinery of various sorts, and for haulage purposes.

The primary object of the invention is to provide a structure that can be used with an ordinary sprocket-wheel and is very inexpensive to construct when compared to link belts now in general use. At the same time it is exceedingly strong and durable.

Another object is to provide for taking up the slack and allowing for the expansion and contraction of the belt.

Various embodiments of the invention are illustrated in the accompanying drawings and described in the following specification, and it will be seen upon an inspection of the claims hereto appended that the invention is open to changes and modifications. It will also be observed that features are embodied in the present case which are illustrated and claimed in a copending application filed by me on July 16, 1902, Serial No. 115,825, but no claim is made herein to any of these features.

In the drawings, Figure 1 is a top plan view of a portion of a driving-belt constructed in accordance with the present invention. Fig. 2 is a horizontal sectional view through a portion of the same. Fig. 3 is a vertical longitudinal section. Fig. 4 is a transverse section taken on the line 4 4 of Fig. 2. Fig. 5 is a similar section taken on the line 5 5 of Fig. 2. Figs. 6 and 7 are also transverse sectional views taken, respectively, on the lines 6 6 and 7 7 of Fig. 2. Fig. 8 is a top plan view of a portion of a belt when used for haulage purposes in coal-mines and similar institutions, this view also illustrating the preferred means employed for shortening and lengthening the belt. Fig. 9 is a detail sectional view through a portion of the above-mentioned means. Fig. 10 is a cross-sectional view more clearly illustrating the guides for the belt. Fig. 11 is a

detail sectional view of a portion of the belt-adjusting means.

Similar numerals of reference designate corresponding parts in all the figures of the drawings.

In the embodiment of the invention as shown a pair of continuous cables 10 are employed, preferably though not necessarily constructed of wire rope and arranged in parallel relation. These cables are connected at suitable intervals by abutments 11, preferably in the form of metallic blocks having longitudinal parallel bores therethrough through which the cable passes. These bores each have an intermediate portion 12 of larger diameter than the diameters of the cables, while the end portions of said bores are contracted, as shown at 13, to the size of the cables, which therefore snugly pass through the same. The terminals 14 of the bores, however, are flared, as shown. The intermediate enlarged portions 12 are filled with suitable metal (preferably babbitt) 15, which is poured while in a molten state through openings 16, formed in the walls of the abutments, said babbitt filling said openings and forming lugs 17, which interlock with the abutments. The metal also interlocks with the cables, and thus said abutments are held against relative movement upon the cables. The advantages for the particular construction of the bores with their flaring ends and the filling of metal has been fully explained in the above-mentioned application and it is believed to be unnecessary to reiterate it in this specification.

Between the various abutments 11 each cable is surrounded and inclosed by a sleeve 18, said sleeves being entirely independent of each other and having their ends spaced a slight distance from the adjacent ends of the abutment. The bores through these sleeves are constructed exactly the same as those above described, and indeed the sleeves are similar in all respects to those set forth in the copending application. They constitute protecting devices for the cables and being spaced apart in the manner shown do not interfere with the insertion of the teeth between the cables and the abutments.

The cable as thus far described is capable

of use for various purposes, but in Figs. 8 to 11, inclusive, there is shown a structure designed especially for hauling cars in coal and other mines. In this structure guideways 19 are formed on opposite sides of the belt by means of spaced sets of strips 20, and outstanding fingers 21, carried by certain of the abutments, project into and are movable in said guideways. These fingers preferably 10 extend entirely across and embrace the abutment, being welded or otherwise secured in place. An upright stem or standard 22, also carried by the abutment, passes through the same and through the fingers, thus securely 15 fastening them together. This standard is arranged to engage a car, which is thus carried along with the belt.

In order to slacken and tighten the cable as may be necessary the following mechanism 20 is employed: The terminals of each cable are fitted in socketed heads 23, being held in place by Babbitt metal 24, poured therein, and said heads are arranged in opposing relation. They are connected by turnbuckles comprising 25 threaded shanks 25, having eyes 26 at their outer ends through which are passed pins 27, that are fastened to the heads. The shanks in turn are connected by the buckles 28, so that by turning said buckles the ends 30 of the cables may be drawn toward each other. This mechanism takes the place of one of the abutments, and it is therefore necessary to provide bearings for the teeth of the sprocket-wheels. These bearings are shown in the 35 form of metallic plates 29, which are located in rear of the heads 23 and extend across the space between the cables, as shown in Fig. 8.

It will be apparent to those skilled in the art that this belt can be used with the well-known forms of sprocket-wheels the teeth of 40 which pass between the cables and engage the ends of the abutments. The structure is exceedingly strong, and the amount of exposed cable is sufficient to permit the belt 45 passing around the sprocket-wheels without straining or injuring it. The cables do away with the necessity of pivoted joints, in which there is necessarily a great amount of wear, and, furthermore, they are protected to a 50 great extent by the inclosed sleeves and abutments. The guiding mechanism employed serves to prevent twisting of the belt, so that the standards always maintain their upright positions, and thus their engagements with 55 the cars are assured.

From the foregoing it is thought that the construction, operation, and many advantages of the herein-described invention will be apparent to those skilled in the art with 60 out further description, and it will be understood that various changes in the size, shape, proportion, and minor details of construction may be resorted to without departing from the spirit or sacrificing any of the advantages 65 of the invention.

Having thus described my invention, what I claim as new, and desire to secure by Letters Patent, is—

1. In a belt of the class described, the combination with an abutment having bores, the intermediate portions of which are enlarged, the end portions being flared, of cables passing through the bores of the abutment, and fillings of metal cast within the enlarged portions of the bores and engaging the cables, 75 said cables being laterally movable in the flared ends of the bores.

2. In a belt of the class described, the combination with longitudinally-disposed cables, of spaced abutments connecting the cables 80 and extending across the same at separated points, and protecting devices located on each cable between the abutments and leaving a space between the same and between each other.

3. In a belt of the class described, the combination with longitudinally-disposed cables, of spaced abutments connecting the cables at 85 separated points, and separate spaced sleeves surrounding each cable between the abutments.

4. In a belt of the class described, the combination with longitudinally-disposed cables, of spaced abutments connecting the cables at 90 separated points, and separate spaced sleeves surrounding each cable between the abutments, said sleeves having their ends spaced from the abutments.

5. The combination with a belt, of a wheel-engaging abutment secured thereto, spaced 100 guideways arranged on opposite sides of the belt, and a guide-finger extending across the abutment and engaging in the guideways, said finger embracing the abutment and projecting beyond the sides thereof.

6. The combination with a belt, of an abutment secured thereto, guideways arranged on opposite sides of the belt, and a guide-finger extending across the abutment and comprising 110 separate sections secured together and extending on opposite sides of said abutment, said finger having its ends slidably engaging in the guideways.

7. The combination with spaced cables, of an abutment connecting the cables, a guide-finger extending across and beyond the abutment, said finger comprising sections that embrace the abutment, and a standard extending through the finger-sections and the abutment between the cables.

8. The combination with spaced guideways, of a plurality of spaced cables arranged between the guideways, and abutments secured to and extending across the space between the cables, guide-fingers extending across the 125 abutment and engaging in the guideways, and a standard passing through the abutment and fingers and arranged to engage a car.

9. In a belt of the class described, the combination with spaced cables, of abutments 130

connecting and secured to the cables, and a turnbuckle connecting the terminals of each cable.

10. In a belt of the class described, the combination with spaced cables, of abutments connecting and secured to the cables, a turnbuckle connecting the terminals of each cable, and bearing - plates connecting the corresponding ends of the turnbuckles.

11. In car-haulage mechanism, the combination with spaced guideways, of a cable running longitudinally between the guideways, sprocket-wheel-engaging abutments secured to the cable at separated points, outstanding fingers mounted upon one of the abutments and engaging in the guideways to prevent the rotation of the cables and abutments, and an upstanding car-engaging standard carried by one of the abutments, said standard projecting above the guideways and being adapted to engage a car.

12. In car-haulage mechanism, the combination with spaced guideways, of spaced cables located between the guideways, spaced wheel - engaging abutments connecting the

guideways, outstanding fingers arranged between the ends of the abutments and slidably engaging in the guideways, and an upstanding standard carried by one of the abutments and arranged to engage a car, said standard projecting above the upper faces of the guideways.

13. In car-haulage mechanism, the combination with spaced guideways, of spaced cables arranged between the guideways, abutments connecting the cables at separated points and arranged between the guideways, separate spaced sleeves surrounding the cables between the abutments, outstanding fingers carried by the abutments and engaging in the guideways, and car-engaging devices carried by certain abutments and being arranged to engage a car located over the cables.

In testimony that I claim the foregoing as my own I have hereto affixed my signature in the presence of two witnesses.

GEORGE S. INGLE.
